DRIP COLLECTOR

Homer S. Safrit, Albemarle, N. C.

Application May 15, 1939, Serial No. 273,740

2 Claims. (Cl. 126—214)

This invention relates to an attachment for oil burning cook stoves.

The invention has for its object to provide an attachment for fitting within the top opening and under the cooking grill of the stove and which is so formed as to constitute a collector for any overflow or drippings from cooking utensils, such as pots and pans, and at the same time provide a protector for the lower parts of the stove, more particularly the chimneys of the oil burners forming elements of the stove, as the collector acts to prevent the depositing on such chimneys of grease, water, soups or anything else that may tend to overflow through the grill of the stove and carbonize on the hot chimneys when the burners are active during the cooking operation.

A further object of the invention is to provide, in a manner as hereinafter set forth, a collector for the purpose referred to of a capacity to take care of any ordinary overflow from cooking utensils, such as pots and pans.

A further object of the invention is to provide, in a manner as hereinafter set forth, a collector for the purpose referred to of a depth to take care of any ordinary overflow from pots and pans, having a capacity of approximately half a gallon, when set quite level, and yet not of a depth to hinder the operation of turnback chimneys now commonly used on oil burning cook stoves.

A further object of the invention is to provide, in a manner as hereinafter set forth, a collector for the purpose referred to which may be adjusted for use on any standard make of oil burning cook stoves.

A further object of the invention is to provide, in a manner as hereinafter set forth, a collector for the purpose referred to for disposing below and in proximity to the cooking grill of an oil burning cook stove and with the collector being so formed to prevent any hindrance to circulation from the top of the chimneys of the burners to cause the chimneys to choke up or smoke.

Further objects of the invention are to provide, in a manner as hereinafter set forth, a collector for the purpose referred to which is simple in its construction, strong, durable, compact, readily installed in an oil burning cook stove with respect to the cooking grill of the latter, thoroughly efficient in its use, and inexpensive to manufacture.

Embodying the objects aforesaid and others which may hereinafter appear the invention consists of the novel construction, combination and

arrangement of parts as will be more specifically referred to and illustrated in the accompanying drawing, wherein is shown an embodiment of this invention, but it is to be understood that changes, variations and modifications may be resorted to which fall within the scope of the invention as claimed.

The collector, which also may be termed a drip or grease receiving pan, is to include a plurality of openings corresponding in number to the number of the oil burners of the stove and upstanding collars corresponding in form to and providing upward continuations of the walls or edges of the openings. The openings are to be disposed in the collector in the same manner as the oil burners are disposed in the stove. The openings are to be arranged directly over the oil burners. The body of the collector is to be arranged in such relation to the chimneys of the burners as not to hinder the turnback of the chimneys. By way of example, the embodiment of the invention as shown is formed with a plurality of openings disposed in a triangular row for arranging above a plurality of oil burners also disposed in a triangular row. When the collector is arranged in protecting position it is suspended in the top opening of and in proximity to the cooking grill of the oil burning cook stove. The openings in the collector are to be positioned below those parts of the said grill directly above the burners and on which are to be positioned the cooking utensils, such as pots and pans.

In the drawing:

Figure 1 is a fragmentary view in front elevation and in dotted lines of an oil burning cook stove showing the adaptation therewith, in full lines of a collector in accordance with this invention.

Figure 2 is a top plan view of the collector.

Figure 3 is a section on lines 3—3 Figure 2 illustrating corresponding parts of the collector.

Figure 4 is a section on lines 4—4 Figure 2 illustrating other corresponding parts of the collector.

Figure 5 is a section on lines 5—5 Figure 2 illustrating still other corresponding parts of the collector, and

Figure 6 is a section on lines 6—6 Figure 2 illustrating still other corresponding parts of the collector.

The embodiment of the invention as shown includes a rectangular plate 1 of sheet metal of the desired gage formed with wide rounded corners 2, front and rear longitudinal edges 3, 55

4 respectively merging into one end of the corners 2 and a pair of end edges 5, 6 merging into the other end of the corners 2. The edges 3, 4, 5, 6 are straight. The edges 3, 4 are disposed at 5 right angles to the edges 5, 6. The plate 1 is formed with a plurality of openings, as shown by way of example three in number and indicated at 7, 8, 9. The opening 7 disposed on one side of the longitudinal median of plate 1, intersected centrally by the horizontal median of the plate 1, arranged between said longitudinal median and edge 4, spaced from the latter and also spaced from the edges 5, 6. The openings 8, 9 are arranged on the other side of the longitudinal median of plate 1 and spaced from edge 3. The opening 8 is disposed on one side of the transverse median of plate 1. The opening 9 is disposed on the other side of said transverse median. The openings 8, 9 are arranged between 10 said transverse median and the said edges 5, 6 respectively.

The plate 1 is provided with an upstanding endless rim 10 formed of curved corner portions 11, a front portion 12, a rear portion 13 and a pair of side portions 14, 15. The portions 11 correspond in contour to the rounded corners 2 and are flush with the latter. The portions 12, 13, 14, 15 correspond in length to and are flush with the edges 3, 4, 5, 6 respectively. The portions 12, 13, 14, 15 are of greater height than and merge into the corner portions 11. The portions 12, 13, 14, 15 merge at their upper ends into outwardly directed flanges 16 disposed at right angles thereto. These flanges correspond in 20 length to the portions 12, 13, 14, 15 and constitute bearings or abutments adapted to bear against the lower face of the cooking grill 17 of the stove 18 when the collector is mounted in the opening 19 at the upper portion of the stove 40 as shown. The flanges 16 space plate 1 from the grill 17. The collector when mounted in the opening 19 is suitably suspended from the side walls 20 of opening 19 in a known manner such as drip pans are secured in gas and oil 45 burning cook stoves.

The plate 1 is formed with a plurality of upstanding collars 21 corresponding in number to the number of the openings aforesaid. The inner faces of the collars 21 form upward continuations 50 of the walls or edges of the openings aforesaid. The contour of the openings, and as shown the openings are by way of example as of circular form. The height of the collars 21 will correspond to the height of the corner portions 11 of the rim 55 10. The diameter of the openings and the collars will be uniform and of greater diameter than the

diameter of the chimneys 22 of the burners 23. The reduced non-flanged wide rounded corner portions 11 coact with the ends of the flanged rim portions, which are of greater height than the corner portions to provide selectable outlet 5 passages to facilitate the discharge of the collected matter when dumping the collector.

It is readily obvious that a collector constructed as aforesaid and arranged in relation to the cooking grill as stated will act as a protecting 10 medium for the purpose heretofore referred to.

Preferably the collector will be stamped from a single sheet of metallic material of the desired gauge, but it is obvious that the rim and collars may be formed separately and then secured to 15 the plate.

What I claim is:

1. In a collector for the purpose set forth, a plate having wide rounded corners and a plurality of spaced openings, an upstanding endless rim integral with the plate and formed with spaced elongated high portions and spaced wide rounded low portions between and merging into the ends of said high portions, said low portions forming upward continuations of the wide rounded corners of said plate and providing the corners of the rim, upstanding collars integral with the plate and forming upward continuations of the walls of said openings and spaced from said rim, said low portions of the rim coacting with the 30 ends of the high portions to provide selectable outlet passages to facilitate the discharge of the collected matter when dumping the collector, and outwardly directed lateral flanges at the tops of said high portions for removably suspending the collector from a support. 35

2. In a collector for the purpose set forth, a plate having wide rounded corners and a plurality of spaced openings, an upstanding endless rim integral with the plate and formed with spaced 40 elongated high portions and spaced wide rounded low portions between and merging into the ends of said high portions, said low portions forming the corners of the rim, upstanding collars integral with the plate and forming upward continuations 45 of the walls of said openings and spaced from said rim, said low portions of the rim coacting with the ends of the high portions to provide selectable outlet passages to facilitate the discharge of the collected matter when dumping the 50 collector, and outwardly directed lateral flanges at the tops of said high portions for removably suspending the collector from a support, said collars being of less height than the said high portions of the rim. 55
